W. J. Ryan

WITNESS:

UNITED STATES PATENT OFFICE.

WILLIAM J. RYAN, OF BRIDGEWATER, SOUTH DAKOTA, ASSIGNOR TO MARY F. RYAN,
OF BRIDGEWATER, SOUTH DAKOTA.

MAIL-SACK LABEL HOLDER.

Application filed February 5, 1923. Serial No. 617,025.

To all whom it may concern:

Be it known that I, WILLIAM J. RYAN, a citizen of the United States, residing at Bridgewater, in the county of McCook and 5 State of South Dakota, have invented new and useful Improvements in Mail-Sack Label Holders, of which the following is a specification.

This invention relates to mail sacks and 10 has for its object the provision of a novel label holder and securing device embodying several features of advantage, one of which is the provision of means within the device for holding the label instead of providing 15 an exteriorly mounted holder as is the common practice.

An important object is the provision of a device of this character in which the label will automatically fall out when the 20 holder is opened at the time it is removed from the mail sack.

Another object is the provision of a device 25 of this character which when applied will automatically lock upon the securing cords of the sack so that when a pad lock is subsequently applied to the device removal of the label holder will be prevented.

An additional object is the provision of a device of this character which will be 30 simple and inexpensive in manufacture, highly efficient in use, durable in service and a general improvement in the art.

With the above and other objects and advantages in view the invention consists in 35 the details of construction to be hereinafter more fully described and claimed and illustrated in the accompanying drawings, in which:

Figure 1 is a perspective view of the 40 device applied,

Figure 2 is a longitudinal section,

Figure 3 is a cross section, taken on the line 3—3 of Figure 2,

Figure 4 is a plan view with the slotted 45 cover plate removed.

Figure 5 is a detail cross section on the line 5—5 of Figure 2 and

Figure 6 is a cross section on the line 6—6 of Figure 2.

50 Referring more particularly to the drawings the letter A represents a mail sack and B designates the cords thereof. In carrying out my invention I provide an elongated trough like member 10 constructed of sheet metal such as galvanized iron or the like

and having one end provided with guides 11 for the passage of the cords B, it being intended that these cords be threaded through the device from the other end thereof. Extending from the main wall 60 of this member 10 near the guides 11 is a staple 12 which projects beyond the open side of the member. Secured within the member 10, as for instance, by soldering 65 is a plate 13 formed at its ends with upturned lips 14 and which serves to hold a label C such as is used on mail sacks for bearing the name of the destination of the mail.

The numeral 15 represents the cover 70 which is of substantially the same length as the member 10 and which is likewise trough shaped and which is disposed with its side flanges in straddling relation to the member 10, the two members being pivotally 75 connected by a pintle pin 16. The free end of the cover is formed with a slot 17 for the passage of the staple 12, while the intermediate portion is provided with a slot 18 permitting inspection of the label, this 80 slot 18 being provided at its ends with inwardly extending flanges 19 which engage the end portions of the label for holding it firmly upon the plate 13. At its pivoted end the cover is provided with a 85 cam 20 which bightingly engages and squeezes the cords B when the cover is swung down onto the member 10. This lock or grip prevents removal of the holder from the cords until the device is opened up at 90 the destination of the mail sack. It is intended that an ordinary pad lock D be applied to the staple 12 as the cover is closed.

From the foregoing description and a 95 study of the drawings it will be apparent that I have thus provided a very simply constructed and consequently inexpensive holder for the labels of mail sacks which has several advantages. An important feature 100 is the fact that the label is easily laid in place when the cover is opened instead of being slid into a retaining member as is the common practice. This placing of the label in the device avoids all possibility of tearing, wrinkling or otherwise damaging the label and the operation is far quicker than under the old method. Another feature is that when the device is opened up to permit 105 its removal from the mail sack the label will 110

fall out instead of being picked away, an operation which is more or less tedious. Owing to the simplicity of the construction and the fewness of the parts it is apparent that there is nothing to get out of order so that the device should have a long life and satisfactorily perform all of its functions.

While I have shown and described the preferred embodiment of the invention it is 10 of course to be understood that I reserve the right to make such changes in the form, construction and arrangement of parts as will not depart from the spirit of the invention or the scope of the subjoined claims.

15 Having thus described my invention I claim:

1. A holder for mail sack labels comprising an elongated trough like body open at both ends and adapted to receive the cords 20 of a mail sack, the cords being passed through the body from end to end thereof, a cover hinged upon one end of the body and swingable toward and from the same, and a clamping cam on the hinge adapted to engage the cords for compressing the same 25 against the bottom of the body.

2. A holder for mail sack labels comprising an elongated trough like body open at both ends and adapted to receive the cords

of a mail sack, the cords being passed 30 through the body from end to end thereof, a cover hinged upon one end of the body and swingable toward and from the same, and a clamping cam on the hinge adapted to engage the cords for compressing the same 35 against the bottom of the body, a staple projecting from the body, and the cover having a slot for the passage of said staple, the staple being adapted to have engaged thereon the shackle of a pad lock for effecting 40 securing.

3. A holder for mail sack labels, comprising an elongated trough like body member provided at one end with guides and adapted to receive the cords of a mail sack, the cords being passed through said guides, a staple on the back wall of said body member projecting beyond the opened front thereof, a label holder within said body, a cover pivoted at one end beyond the body and adapted to close the open front thereof, said cover being formed with a slot for the passage of said staple and an opening exposing the label, and a locking cam at the hinged end of the cover squeezingly engaging said 50 cords.

In testimony whereof I affix my signature.
WILLIAM J. RYAN.
